UNITED STATES PATENT OFFICE.

PHILIP D. PARSONS, OF PHILADELPHIA, PENNSYLVANIA, ASSIGNOR, BY MESNE ASSIGNMENTS, TO SCOTT PAPER COMPANY, A CORPORATION OF PENNSYLVANIA.

MACHINE FOR INSERTING SUSPENSION DEVICES IN TOILET-PAPER PACKAGES.

Application filed February 25, 1922. Serial No. 539,318.

To all whom it may concern:

Be it known that I, PHILIP D. PARSONS, a citizen of the United States, and resident of Philadelphia, county of Philadelphia, and State of Pennsylvania, have invented an Improvement in Machines for Inserting Suspension Devices in Toilet-Paper Packages, of which the following is a specification.

10 The object of my invention is to provide an automatic machine for perforating toilet paper packages and inserting through the perforation a metallic tongue of a suspension device, whereby the package is adapted 15 to be suspended in a dispensing cabinet.

My object is further to provide a construction of machine which shall operate in a continuous and automatic manner with accuracy and which shall receive the paper 20 packages on a suitable conveying device preferably of a turret type which successively brings the package into alinement with a perforating mechanism and thereafter with a mechanism for introducing a 25 suspension device through the perforation for uniting the sheets into a package and providing means for suspension thereof, and finally automatically discharging the 30 same; said operations being performed under definite control.

My invention also consists of improvements hereinafter described whereby the above objects and results are attained, said improvements comprising certain organization, 35 combination of parts which are fully described hereinafter and more particularly defined in the claims.

Referring to the drawings: Fig. 1 is a plan view of a machine embodying my invention; Fig. 2 is a vertical sectional view 40 of my improved machine taken on line 2—2 of Fig. 1; Fig. 3 is a front elevation of the machine; Fig. 4 is an elevation of the mechanism for inserting the suspension device; Fig. 5 is a perspective view illustrating a portion of the paper package after it 45 has been perforated; Fig. 6 is a similar view with the suspension device applied through the perforation and clinched to the paper; and Fig. 7 is a skeleton perspective view of the operating devices of the mechanism for applying the suspension device to the paper package.

2 is the table or main frame of the ma-

chine. 3 represents a turret supported above the table and journaled upon an upright stud 3^a whereby it may rotate in a horizontal plane. The turret is preferably made octagonal and provided with a plurality of box-like receptacles 4 secured to and rotating from the turret proper, as indicated more fully in Fig. 1. These box-like receptacles are provided with sides but are open at the ends and are adapted to receive the paper packages 56, and convey them during the rotation of the turret successively in alinement with a perforating or stabbing machine 28 and a suspension applying mechanism 29. The paper packages 56 may be fed into the box-like receptacles 4 by hand or in any other suitable manner. Preferably, I employ the following mechanism.

An endless apron 5 is guided over rollers 6 and 7 for receiving the paper packages and conveying them to a position indicated in Fig. 1. If desired, these rollers 6 and 7 may be connected by chains and sprocket wheels, though this is not essential. At each side of the travelling apron 5 is arranged an upright guide wall 8 between which the paper package is guided and to facilitate the introduction of the paper package the outermost ends of these guide walls 8 may be slightly flared. When the package of paper 56 has been conveyed by the apron 5 to the position indicated in Fig. 1, it is received against a plate 9 which limits its travel and positions it in accurate alinement with the box-like receptacle 4 into which it is to be shifted. To transfer the paper package into the box-like structure 4 of the turret, I provide the pusher device 10 which is secured to a horizontal shaft 11 carried in suitable guides 12 and 12^a, the former being supported upon the upper end of the stud 3^a and in that manner centralizes the shaft 11 in respect to the axis of the turret. To the extreme end of the shaft 11 is a downwardly extending arm 11^a which is secured to a rod 13 (parallel to the upper rod 11) and which is reciprocated by a hinged arm 14 which receives motion from a crank wheel 16 by means of a link 15 (Fig. 3).

The particular mechanism for insuring the timing action whereby the reciprocations of the rod 11 and the pusher arm 10 are caused

to properly shift the paper package into the box-like receptacle, will be described hereinafter.

Referring now to the device for perforating the paper, this will be understood more particularly by a reference to Fig. 2, wherein it is shown in section. 28' is the main frame of this part of the device and carries at its upper end a horizontal crank shaft 34 provided at one end with the crank 33 and at the other end with the belt wheel 27, by which power is imparted to the machine. At the front end of the main frame 28' is a head 30 in which a vertically reciprocating plunger 31 is guided and caused to reciprocate by means of a link 35 pivoted to the crank 33. Secured to and projecting downward from the plunger 31 is the perforating or stabbing blade 32. Slidably connected at the front of the head 30 is a presser foot 36 which is adapted to move vertically under the action of the two springs 38 and 39 between which is arranged a block 37 connected with the plunger 31. It will now be understood that as the plunger 31 rises, the spring 39 raises the presser foot sufficiently to allow the paper package to be conveyed under it and thereafter, when the plunger 31 is driven downward for the purpose of perforating the package, the spring 38 is put under compression and forces the presser foot 36 tightly upon the paper package simultaneously with the descent of the perforating blade or knife 32. In this manner, the paper package is firmly held during the perforating thereof. As soon as the perforating of the paper is completed, the perforating blade 32 is raised with the plunger 31 while the presser foot 36 still maintains pressure upon the paper and thereby acts as a stripper to prevent the rise of the paper while the blade is being withdrawn. As soon as the blade has left the paper, the presser foot is raised by the final upward movement of the plunger, so as to be out of the way when the turret takes a further horizontal motion to convey the perforated paper to the mechanism for inserting the suspension device. In addition to the mechanism which has been described in connection with the perforating or stabbing devices, there is pivoted to the head 30, adjacent to the lower part thereof, a plate 40 whose function is to press upon the outer end of the package of paper to press it backward in the box-like receptacle 4, so as to insure having all of the paper packages in accurate position at the time that the perforation is made. A spring 41 operates to move this plate 40 away from the box-like receptacle containing the paper and an arm 42 secured to the plunger 31 is adapted to press upon the outer side of the plate 40, and as the plunger descends, the arm 42 rapidly presses the

plate toward the end of the paper package, so that the paper package is definitely positioned and held against displacement in a longitudinal direction, during the descent of the perforating blade. As soon as the plunger 31 rises, the arm 42 also rises and the spring 41 once more withdraws the plate 40 from the paper package and permits it to be conveyed by the turret to the mechanism for inserting the suspension device comprising the tongue 54 and the socket portion 53, which is clearly shown in Fig. 6. The paper package, when perforated, will have the incision 57 arranged in the middle as to width and close to one end of the package longitudinally considered, as will be understood by reference to Fig. 5, which shows the perforated end of a package. The package, so perforated, is next moved to a position beneath the suspension applying mechanism 29, as shown in Figs. 1 and 4, wherein the box-like receptacle 4 is shown as being positioned immediately below the operating mechanism for inserting the suspension device.

More specifically referring to this mechanism 29, there is a table 45 provided with a horizontally reciprocating feeding blade 46, the forward end of which is provided with two arms having their opposing edges beveled, so as to receive a triangular shaped socket part 53 of the suspension device (Fig. 7). Immediately over this blade is a vertical guide-way 44 of any suitable construction through which the suspension devices 53 are caused to pass downwardly by gravity, and the lowermost of these suspension devices is brought into position whereby the beveled arms of the plate 46 are in position to cooperate in such manner as to push the socket portion 53 forward beneath the plunger 43 which is arranged to reciprocate vertically in the frame 43a. The lower part of this plunger 43 is provided on opposite sides with the spring actuated jaws 58a which are notched at their free ends so as to receive and grip the socket portion 53 at its widest end. A pivoted support 58 is also yieldingly hinged to the lower end of the plunger 43 to receive and support the wide end of the socket portion 53 of the suspension device during the descent of the plunger and when the tongue 54 is being driven through the perforation 57 in the paper package. Before the plunger 43 descends, the sliding plate 46 is withdrawn and leaves the suspension device 53-54 in the custody of the jaws 58 and 58a at the bottom of the plunger. The plunger thereupon is driven downward and when the end of the tongue 54 passes through the paper package, it is received upon an anvil 54a which causes it to be bent sideways, as indicated at 55 in Fig. 6, so that said suspension device is clinched in position upon the

paper package. When this action is accomplished, the plunger 43 ascends and the spring actuated jaws 58 and 58^a are released from the socket portion 53 of the suspension device and rise to a position suitable for the reception of the socket portion of another suspension device.

The means for reciprocating the plunger 43 comprises the following instrumentalities. Extending laterally from the plunger 31 of the perforating device is a horizontal arm 52 which extends through the vertical slot in the plunger 43. This plunger furthermore, is provided with sockets in which coiled springs 59 and 60 are respectively arranged one below and the other above the said arm 52, (Fig. 4). It will now be understood that when the plunger 31 descends, the arm 52 descends with it, so that at the same time that the perforated blade 32 comes into action to perforate one package of paper, the plunger 43 is driven downward for inserting the suspension device in the perforation of a previously prepared package. The employment of the spring 59 permits the suspension device to be driven tightly down upon the paper package but with sufficient yieldingness that no undue pressure will be applied. Similarly, the spring 60 permits the arm 52 to move somewhat after the plunger 43 has been raised to the full height and into accurate alignment to receive the next suspension device.

The mechanism for operating the plate 46 for feeding the suspension device into alignment with the plunger 43 consists of the following parts: A lever 47 is pivoted to the stationary frame at 48 providing a short arm which is hinged to a horizontal sliding block 49 and a long arm which is connected with the reciprocating plate 46. The forward end of the block 49 is beveled, as at 49^a and cooperates with a roller 51 journaled upon the vertical reciprocating plunger 43. A coiled spring 50 having one end connected to the stationary frame and the other end to the sliding block 49, operates to move the block toward the roller 51 and to withdraw the plate 46 backward from the plunger 43. When, however, the plunger 43 is fully elevated, as indicated in Figs. 4 and 7, it forces the block 49 to the left and moves the sliding plate 46 into the position necessary for feeding the socket portion 53 of the suspension device to a position immediately beneath the plunger. When the plunger 43 descends, the block 49 is released, the spring 50 comes into play, the lever 47 is swung backward at its lower part, and the plate 46 is withdrawn to a position to receive the next suspension device, all of which will be readily understood by reference to Fig. 7, supplemented by Fig. 4.

When the paper package has been thus

supplied with the suspension device, it will be of the construction illustrated in Fig. 6, and is then conveyed by the rotation of the turret to a position in alinement with a delivery apron 27. When in this position, a discharging arm 28^a secured to the rod 11 will discharge the package from the box-like receptacle 4 to the delivery apron 27. This discharging operation of the arm 28^a is coincident with the feeding operation of the arm 10 on the same rod, so that when one package is delivered to the box-like receptacle of the turret, the completed package is discharged from another of the box-like receptacles of the turret and consequently the operation of the machine through the several stages of manipulation is done in a continuous manner.

For obtaining an intermittent action of the feeding and discharging rod 11 and for operating the feeding apron for delivering assembled sheets into the machine, the following mechanism may be employed. From the belt driven shaft 34, chain and sprocket transmission 26 imparts rotation to a shaft 21 below the table, the said shaft driving the vertical shaft 18^a by means of miter gears 18. The upper end of the shaft 18^a is provided with one member of a Geneva transmission 20, the other member of which is secured to the turret 3.

The Geneva transmission is of the usual form in which each revolution of the shaft 18^a and its member imparts intermittently rotary motion through the other member to the turret and thereupon holds the latter stationary through the remainder of the revolution of the said shaft 18^a. This mechanism gives an intermittent rotary motion to the turret from a continuously driven shaft, all of which will be understood by reference to Figs. 1 and 2.

The shaft 21 is further geared by miter gears 22 with a shaft 23 at right angles and having at its distant end a connection by chain and sprocket gears 24 with the driving means for the endless belt 5 for feeding the assembled sheets into the machine. The shaft 21 is also geared by means of spur gearing 25 with the shaft carrying the gear 17 which is of a construction having one-half of its circumference provided with teeth and the remaining half cylindrical without teeth. Arranged adjacent to the gear 17 and intermittently rotated by it, is the crank gear 16 to which the link 15 is pivoted as before referred to. The link 15 operates the lever 14 and through connections imparts reciprocation to the feeding and discharging rod 11, as before described. The gear 16 has teeth upon the greater part of its circumference to mesh with the teeth on the gear 17, but it has also a blank or wider tooth portion curved to fit the cylindrical part of the gear 17, so

that after a full revolution of the gear 16 by a semirevolution of the gear 17, said gear 16 remains stationary during the second half of the revolution of the gear 17. 5 This mechanism imparts an intermittent action to the rod 11, so that it is inactive during half of the time and active during the remaining half.

I do not confine myself to the various details of means for operating the several active portions of the machine which directly prepare the paper package, as such mechanism may be greatly varied without departing from the spirit of the invention, it 15 merely being necessary to provide intermittent actions in respect to the turret and the feeding and discharge mechanism, which shall operate in timed relation with the means for perforating the paper and introducing the socket member into the perforation and clinching the tongue thereof in position.

While the tongues 54 are provided with the socket parts 53, the invention broadly 25 is for introducing the tongues through the paper packages for holding the sheets in definite relation and this would be the same whether the end of the tongue opposite to the clinched part 55 was provided with the 30 socket 53 or not, and I do not limit myself in this respect.

It will also be understood that ordinarily these paper packages are backed with a sheet of stiff paper or light cardboard which 35 is held in place by the socket portion 53 and tongue, such backing merely constituting a thick sheet at one side of the package; and while this is not material to the invention, in practice, the heavy sheet prevents the 40 light tissue paper of the packages curling upward or becoming deranged.

It will now be apparent that I have devised a novel and useful construction which embodies the features of advantage enumerated as desirable, and while I have in the present instance shown and described the preferred embodiment thereof which has been found in practice to give satisfactory 45 and reliable results, it is to be understood that I do not restrict myself to the details, as the same are susceptible of modification in various particulars without departing from the spirit or scope of the invention.

Having now described my invention, 50 what I claim as new and desire to secure by Letters Patent is:—

1. In a machine of the character stated, the combination of a perforating mechanism having a vertically reciprocable perforating member for perforating a paper package, with a vertically reciprocating mechanism for inserting a metallic tongue through the perforation in the paper package for holding the sheets thereof together as a unit, conveying means providing horizontal

surfaces upon which the paper packages lie for successively feeding paper packages to the perforating mechanism and to the metallic tongue inserting mechanism, and means for intermittently operating the 70 conveying means, the perforating mechanism and metallic tongue inserting mechanism in timed relation with respect to each other.

2. The invention according to claim 1, 75 wherein further there is provided automatic means comprising a reciprocating shaft having separate devices movable with the shaft for feeding the paper packages to the horizontal surfaces of the conveying means and for automatically discharging the paper packages after the tongues have been inserted therein.

3. In a machine of the character stated, the combination of a perforating mechanism for perforating a paper package, with mechanism for inserting a metallic tongue through the perforation in the paper package for holding the sheets thereof together as a unit, conveying means for successively feeding paper packages to the perforating mechanism and to the metallic tongue inserting mechanism, means for intermittently operating the conveying means, the perforating mechanism and the metallic tongue inserting mechanism in timed relation with respect to each other, said conveying means comprising a turret structure having receptacles arranged about its perimeter for receiving and holding the paper packages, and power devices for intermittently operating the turret whereby it has a step by step motion.

4. The invention according to claim 3, 105 wherein the receptacles of the turret are box-shaped having their top and outer ends open and are so spaced in relation to each other that one of the receptacles will be in position below the perforating mechanism while another of the receptacles is in position beneath the mechanism for inserting the tongue device through the paper package.

5. The invention according to claim 3, 115 wherein means are provided for feeding the paper packages into the receptacles of the turret prior to their presentation to the perforating mechanism and for delivering the packages from the turret receptacles after they have left the metallic tongue inserting mechanism.

6. In a machine of the character stated, the combination of a perforating mechanism for perforating a paper package, with mechanism for inserting a metallic tongue through the perforation in the paper package for holding the sheets thereof together as a unit, conveying means for successively feeding paper packages to the perforating mechanism and to the metallic tongue in- 125

serting mechanism, means for intermittently operating the conveying means, the perforating mechanism and the metallic tongue inserting mechanism in timed relation with respect to each other, said conveying means comprising a turret structure having receptacles arranged about its perimeter for receiving and holding the paper packages, power devices for intermittently operating the turret whereby it has a step by step motion, means for feeding the paper packages to and into the receptacles of the turret structure in succession at a point prior to their presentation to the perforating mechanism, and means for delivering the completed packages from the turret receptacles after leaving the metallic tongue inserting mechanism, the feeding and delivery means being operatively connected so that a fresh package is introduced into one of the receptacles of the turret simultaneously with the delivery of a completed package from another of the receptacles thereof.

7. The invention according to claim 6, wherein further connecting and controlling means are provided between the means for feeding the paper packages into and from the receptacles of the turret and the means for operating the perforating mechanism, and metallic tongue inserting mechanism to insure all of said mechanisms operating simultaneously and when the turret is stationary.

8. In a machine of the character stated, the combination of a perforating mechanism for perforating a paper package, with mechanism for inserting a metallic tongue through the perforation in the paper package for holding the sheets thereof together as a unit, conveying means for successively feeding paper packages to the perforating mechanism and to the metallic tongue inserting mechanism, means for intermittently operating the conveying means, the perforating mechanism and the metallic tongue inserting mechanism in timed relation with respect to each other, positively operated power devices for actuating the perforating mechanism, and means indirectly operated by the power devices and connecting with the perforating mechanism for operating the metallic tongue inserting mechanism.

9. In a machine of the character stated, the combination of a perforating mechanism for perforating a paper package, with mechanism for inserting a metallic tongue

through the perforation in the paper package for holding the sheets thereof together as a unit, conveying means for successively feeding paper packages to the perforating mechanism and to the metallic tongue inserting mechanism, means for intermittently operating the conveying means, the perforating mechanism and the metallic tongue inserting mechanism in timed relation with respect to each other, said perforating mechanism comprising a reciprocating head carrying a perforating or stabbing blade, a clamping foot and stripper adjustable to clamp the paper package, and spring pressure devices for applying pressure to the clamp and stripper actuated by the head.

10. The invention according to claim 9, wherein the perforating mechanism is further provided with a hinged mechanism for intermittently pressing upon the end of the paper package to definitely position it under the perforating blade during the perforation of the paper, and means for putting the said hinged mechanism into action before the perforating blade enters the package of paper.

11. In a machine of the character stated, the combination of a perforating mechanism for perforating a paper package, with mechanism for inserting a metallic tongue through the perforation in the paper package for holding the sheets thereof together as a unit, conveying means for successively feeding paper packages to the perforating mechanism and to the metallic tongue inserting mechanism, means for intermittently operating the conveying means, the perforating mechanism and the metallic tongue inserting mechanism in timed relation with respect to each other, said mechanism for inserting the metallic tongue in the perforated paper package comprising a vertical guiding means for receiving and holding a plurality of the tongues and permitting them to be successively brought to a definite level, means for feeding the metallic tongue into position to be driven downward through the perforated paper, and a vertically operable plunger for driving the metallic tongue downward through the perforated paper.

In testimony of which invention, I hereunto set my hand.

PHILIP D. PARSONS.
